(No Model.)

M. BARDILL.

WASH BOILER.

No. 357,895.

Patented Feb. 15, 1887.

UNITED STATES PATENT OFFICE.

MAGGIE BARDILL, OF GROTON, DAKOTA TERRITORY.

WASH-BOILER.

SPECIFICATION forming part of Letters Patent No. 357,895, dated February 15, 1887.

Application filed November 10, 1886. Serial No. 218,459. (No model.)

To all whom it may concern:

Be it known that I, MAGGIE BARDILL, a citizen of the United States, residing at Groton, in the county of Brown and Territory of Dakota, have invented certain new and useful Improvements in Wash-Boilers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to sectional wash-boilers and holders.

The object of this invention is to provide simple, convenient, light, and efficient means for supporting the parts of a sectional wash-boiler; and to that end it consists in the novel features hereinafter set forth and claimed, and shown in the annexed drawings, in which—

Figure 1 is a perspective view of the sectional boiler and holder. Fig. 2 is a central longitudinal sectional view, and Fig. 3 is a perspective view of the holder.

The boiler comprises the two sections A and B, each complete in itself and forming a separate vessel. The two sections, when put together, present the appearance of an ordinary wash-boiler of that type having rounded ends. The section A has side handles, *a*, and cover *a'*, and the section B has corresponding handles, *b*, and cover *b'*. The sections can be moved about as one boiler by supporting them in a holder, the form shown being preferred, because of its lightness in weight, neatness in appearance, simplicity of construction, and openness of structure, whereby the heat of the fire can strike directly upon the bottom of the sections of the boiler, and not be conducted away and lost, as would be the case if the holder were closed, and especially so if the bottom were in one piece, instead of a skeleton rim or frame, as shown.

The holder consists of the supporting-rim D, wire guard C, connecting-wires E and E', and the bails F. The supporting-rim has its outer edge conforming to the outline of the boiler, and upwardly flanged and embracing a portion of the sides of the boiler. It projects inward a sufficient distance to insure a firm purchase for the boiler.

The holder is intended to set over the pot-holes in a manner well understood, and by reason of the space between the rim the heat of the fire can have full play upon the bottom of the sections of the boiler. The strip G is located directly beneath the junction of the two sections, and not only braces the opposite sides of the rim, to which its ends are secured, but supports the inner ends of the sections of the boiler, and prevents the smoke and heat ascending between the ends of said parts.

The wire guard is held to the rim by the connecting-wires E and E'. The connecting-wires E', which are located near each end diametrically opposite each other, are coiled about the guard-wire and extended beyond the same in an upward direction, and terminate in eyes, to which the ends of the bails F are attached.

By having the boiler made in sections different articles of clothing can be boiled at one and the same time, and each be separated from the other. Again, each section can be lifted off or on the stove independently of the other, thus rendering comparatively light the laundry-work of housekeepers, as the strain incident to the lifting of heavy boilers is done away with.

Having thus described my invention, what I claim, and desire to secure by Letters Patent, is—

1. The combination, with the sectional wash-boiler, of the holder having an open bottom, substantially as and for the purpose described.

2. The combination, with the sectional wash-boiler, of the open-bottom holder having a strip located directly beneath the junction of said sections, substantially as and for the purpose described.

3. The herein-described holder, comprising the supporting-rim, the wire guard C, the connecting-wires E E', said wires E' projecting upward beyond the wire guard, and the bails attached to the extended ends of wires E', substantially as set forth.

In testimony whereof I affix my signature in presence of two witnesses.

MAGGIE BARDILL.

Witnesses:

J. S. CARTER,
N. C. MCINTYRE.
